(57) **CLAIM**

The ornamental design for a pyramidal bottle, as shown and described.

DESCRIPTION

FIG. 1 is a front elevated perspective view of a first embodiment of a pyramidal bottle, showing the new design; FIG. 2 is a side view thereof, wherein each of the side views are equivalent;

FIG. 3 is a top view thereof;

FIG. 4 is a bottom view thereof;

FIG. 5 is a side cut-away view thereof;

FIG. 6 is a front elevated perspective view of a second embodiment thereof;

FIG. 7 is a side view thereof, wherein each of the side views are equivalent;

FIG. 8 is a top view thereof;

FIG. 9 is a bottom view thereof; and,

FIG. 10 is side cut-away view thereof.

In all figures, any showing of the environment and/or drawing disclosure and/or vents by broken lines is for illustrative purposes only and forms no part of the claimed design.

1 Claim, 10 Drawing Sheets
